Patented Feb. 11, 1964

197,471

GOLF CLUB PUTTER

Daniel H. Handelan, 4250 N. Marine Drive, Chicago, Ill.

Filed Sept. 23, 1963, Ser. No. 76,675

Term of patent 14 years

(Cl. D34—5)

FIGURE 1 is a front elevational view of the golf club putter showing my new design.

FIGURE 2 is an outer end elevation of the golf club putter of FIGURE 1.

FIGURE 3 is a rear elevational view of the golf club putter of FIGURES 1 and 2.

FIGURE 4 is a top plan view of the golf club putter of this invention.

The fragmentary broken lines indicating a shaft in FIGS. 1, 2 and 3 are for illustrative purposes only.

I claim:

The ornamental design for a golf club putter, as shown and described.
